(57) **CLAIM**

The ornamental design for a audio playback device, as shown and described.

DESCRIPTION

FIG. 1 is a perspective view of a audio playback device showing my new design;

FIG. 2 is a front elevational view thereof;

FIG. 3 is a bottom plan view thereof;

FIG. 4 is a right side elevational view thereof, the left side view being a mirror image;

FIG. 5 is a rear view elevational thereof;

FIG. 6 is front elevational view of an alternate embodiment of FIG. 1; and,

FIG. 7 is top plan view thereof.

The broken line showing of the LCD clock display on FIGS. 2 and 6 is for illustrative purposes only and forms no part of the claimed design.
